UNITED STATES PATENT OFFICE

148,815

DESIGN FOR A COMBINED COMPACT AND LIPSTICK HOLDER

Adolph Olevin, Brooklyn, N. Y.

Application March 30, 1946, Serial No. 128,114

Term of patent 7 years

(Cl. D86—10)

To all whom it may concern:

Be it known that I, Adolph Olevin, a citizen of the United States of America, residing in the Borough of Brooklyn, city of New York, county of Kings, State of New York, have invented a new, original, and ornamental Design for a Combined Compact and Lipstick Holder, of which the following is a specification, reference being had to the accompanying drawing, forming a part thereof.

Figure 1 is a view in perspective of a combined compact and lipstick holder showing my new design; Figure 2 is a perspective view of the combined compact and lipstick holder of Figure 1 as inverted; Figure 3 is a view in perspective of my combined compact and lipstick holder in an open condition thereof; Figure 4 is an enlarged vertical sectional view as seen from the plane 4—4 on Figure 1; and Figure 5 is a view of the crown and lipstick element as withdrawn from the position it occupies in Figure 3.

I claim:

The ornamental design for a combined compact and lipstick holder, shown and described.

ADOLPH OLEVIN.
